(57) **CLAIM**

The ornamental design for a lid, as shown and described.

DESCRIPTION

FIG. 1 is a front left side perspective view showing the new design for a lid;

FIG. 2 is a rear right side perspective view thereof;
FIG. 3 is a right side perspective view taken from underneath thereof;
FIG. 4 is a front elevation view thereof;
FIG. 5 is a rear elevation view thereof;
FIG. 6 is a left side view thereof;
FIG. 7 is a right side view thereof;
FIG. 8 is a top plan view thereof;
FIG. 9 is a bottom plan view thereof;
FIG. 10 is a front left side perspective view thereof illustrating a pour cap in an open configuration;
FIG. 11 is a rear left side perspective view thereof;
FIG. 12 is a rear right side perspective view thereof;
FIG. 13 is a front right side perspective view thereof;
FIG. 14 is a front elevation view thereof;
FIG. 15 is a rear elevation view thereof;
FIG. 16 is a left side view thereof;
FIG. 17 is a right side view thereof;
FIG. 18 is a top plan view thereof;
FIG. 19 is a front left side perspective view thereof illustrating a shaker cap in an open configuration;
FIG. 20 is a rear left side perspective view thereof;
FIG. 21 is a rear right side perspective view thereof;
FIG. 22 is a front right side perspective view thereof;
FIG. 23 is a front elevation view thereof;
FIG. 24 is a rear elevation view thereof;
FIG. 25 is a left side view thereof;
FIG. 26 is a right side view thereof;
FIG. 27 is a top plan view thereof;
FIG. 28 is a front left side perspective view thereof illustrating a full cap in an open configuration;
FIG. 29 is a rear left side perspective view thereof;
FIG. 30 is a right side perspective view taken from underneath thereof;
FIG. 31 is a front elevation view thereof;
FIG. 32 is a rear elevation view thereof;
FIG. 33 is a left side view thereof;
FIG. 34 is a right side view thereof;
FIG. 35 is a top plan view thereof; and,
FIG. 36 is a bottom plan view thereof.

The broken lines in the FIGS. form no part of the claimed design.
